J. E. MCKINLEY

SHEARS SHARPENER

Filed Feb. 24, 1925

INVENTOR
J. E. M^CKINLEY
BY *Marvin Leo.*

ATTORNEYS

UNITED STATES PATENT OFFICE.

JOHN EDGAR MCKINLEY, OF OAKLAND, NEBRASKA, ASSIGNOR OF ONE-FOURTH TO
ROY BOWEN, OF OAKLAND, NEBRASKA.

SHEARS SHARPENER.

Application filed February 24, 1925. Serial No. 11,282.

To all whom it may concern:

Be it known that I, JOHN E. MCKINLEY, a citizen of the United States, and a resident of Oakland, county of Burt, and State of Nebraska, have invented a new and useful Improvement in a Shears Sharpener, of which the following is a full, clear, and exact description.

My invention relates to improvements in 10 shears sharpeners, and it consists in the combinations, constructions, and arrangements herein described and claimed.

An object of my invention is to provide 15 a shears sharpener in which means is provided for producing a uniform and accurate cutting edge to a pair of shears or the like.

A further object of my invention is to provide 20 a device of the character described which is adjustable for sharpening shears having blades of various sizes and cutting edges at various pitches.

A further object of my invention is to provide 25 a device of the character described in which means is provided for permitting the guiding and movement of the abrasive and sharpening means at all times transverse to the cutting edge throughout the entire length of the cutting edge.

A further object of my invention is to 30 provide a device of the character described in which means is provided for supporting and holding a hone and a file each when used in the same relative position to the cutting edge of the blade of the shears secured in the device.

Other objects and advantages will appear 35 in the following specification, and the novel features of the invention will be particularly pointed out in the appended claims.

My invention is illustrated in the accompanying drawings, forming a part of this 40 application, in which

Figure 1 is a side elevation of an embodiment of my invention,

Fig. 2 is a top plan view of the device 45 shown in Fig. 1, and

Fig. 3 is a fragmentary view of the inner face of one of the clamping members for the shears blade.

In carrying out my invention I make use 50 of a body member 1 which has a bracket 2 extending downwardly therefrom and a clamp screw 3 with a thumb grip 4 for securely clamping the body member 1 to a supporting surface 5 such as a table edge 55 or the like.

The body member 1 has an upright post 6 formed integral therewith which terminates at its upper end in one of a pair of vise members 7, see Fig. 2, a complementary vise 60 member 8 having its inner wall curved as shown at 9 is provided and is held in operative engagement with the members 7 by adjustable means comprising a bolt 10 and wing nut 11, the bolt being projected through 65 each of the members so that when the wing-nut is tightened one blade 12 of a pair of shears may be securely held between the vise members 7 and 8.

Means for alining the cutting edge 13 of 70 the blade 12 so that it may lie above and parallel with the vise members is provided in a cam member 14 mounted upon a threaded shaft 15 which is projected through the vise member 7 and rotatably mounted there- 75 in. A thumb-screw 16 is provided for the shaft 15 by means of which the cam member 14 may be held in any one of a plurality of positions, see Fig. 3. Tiny cavities arranged in arcuate alignment with the outer 80 end of the cam member 14 as shown at 17 are provided in the inner face of the vise member 7 and a projection is formed on the inner face of the cam member 14 which is received in the cavities 17 respectively depending upon the position of the cam member.

A substantially horizontal rearwardly extending arm 18 is formed integral with the body member 1 and is perpendicular to the plane of the gripping edges of the vise members 7 and 8 and consequently with the cutting edge 13 of the blade 12.

The outermost end of the arm 18 has a threaded aperture with its axis parallel with the axis of the upright post 6. A threaded stem 19 is projected through this threaded aperture in the arm 18 and a lock nut 20 is

disposed on the stem 19 so as to secure the stem against movement relative to the arm upon the tightening of the nut 20.

5 A horizontal guide bar 21 is supported at the upper end 22 of the stem 19. The normal operative position of the guide bar 21 is parallel with the cutting edge 13 of the blade 12. Upright stop members 22 are formed at each end of the guide bar 21 for 10 the purpose hereinafter described.

15 A combined file and hone supporting member 23 is provided and has a handle portion 24 at one end thereof by means of which the member may be manually grasped and actuated. The outermost end of the body member 23 is provided with a relatively flat portion 25 which is adapted to rest upon the guide member 21. This portion 25 has a longitudinal slot 26 therethrough so as to 20 reduce friction upon the guide member 21 to a minimum when the device is in operation.

25 The member 23 has a cavity extending longitudinally thereof, as shown at 26, into which a hone 27 is placed. The cavity is so constructed as to permit the work engaging surface 28 of the hone to lie substantially contiguous with the adjacent outer surface of the member 23. Clamping means 29 30 associated with the member 23 is provided for removably securing the hone 27 in the cavity 26. Holding members 30 and 31 fixed to the member 23 at the opposite ends of the cavity 26 effectually prevent lateral 35 displacement of the hone while in use.

40 A second cavity 32 is provided in the opposite face of the member 23 and is shallower than the cavity 26, and is for the purpose of receiving the ordinary type of bastard file 33. This type of file is well known in the art and has serrations which cross, certain of the serrations being disposed longitudinally of the file. A clamping member 34 including a thumb screw 35 is 45 carried at the inner end of the member 23 by means of which the file 33 is removably secured and held in place in the cavity 32.

50 From the foregoing description of the device the various parts thereof may be readily understood. The first step in sharpening a shears blade with my improved sharpening device is that of placing the blade 12 between the vise members 7 and 8 and securing the blade with its cutting edge 55 13 parallel with and above the upper edge of the vise members. This is done by adjustment of the cam member 14 and by fixing the position of the cam member against movement by tightening the thumb-nut 16. 60 Next the wing-nut 11 is tightened upon the bolt 10 to draw the vise members together, thus securely holding the blade in the proper position for sharpening.

65 It is then necessary to determine the angle of the cutting edge 13 which may be done

by placing the body member 23 with its file and hone thereupon in the position shown in Figure 1, and in elevating the guide member 21 or lowering the guide member by rotation of the stem 19. When 70 the file or hone, as the case may be, is parallel with the cutting edge 13 the guide member 21 is disposed in the position shown in Fig. 2 with relation to the blade 12 and the nut 20 tightened. 75

Let us assume that it is desired to sharpen the blade 12 so that its cutting edge will have a corrugated surface. This is done with the file 33. Actuation of the member 23 supporting the file will be in straight 80 strokes across the edge 13 and perpendicular thereto. The file should touch the blade only upon the downward stroke and be lifted therefrom on the upward stroke. During the downward stroke it is necessary 85 that the portion 25 of the member 23 contact with and move upon the guide member 21 so as to maintain the inclination of the cutting edge 13 at its proper angle.

The finishing touches to the edge are 90 accomplished by reversing the member 23 and applying the hone 28 thereto.

If a perfectly smooth keen cutting edge is desired, the file 33 is operated with a slight side movement as it is drawn downwardly 95 and cutting may be down or both the down and up strokes. The finishing or honing of the blade is done in the same manner as applies to the use of the file 33 by reversing the member 23. 100

It will be noted that the work engaging surfaces of the portion 25 with relation to the outer faces of the member 23 is identical so that there is no likelihood of cutting the blade of the shears with the file at one 105 angle and with the hone at another angle, even though the hone is thicker than the file.

I claim:

1. A device of the character described comprising a vise adapted to grip and support the blade of a pair of shears, an adjustable guide member disposed at a predetermined distance from said vise and being adjustable as to height, said member having a horizontal supporting surface greater in length than the length of the shears blade and having upturned stop members at each end thereof, and an abradant supporting member having a handle portion for manual actuation, whereby the abradant may be moved across said cutting blade and the member may bear at one end upon and be guided by said guide member. 110 115 120

2. A device of the character described comprising a vise adapted to grip and support the blade of a pair of shears, an adjustable guide member disposed at a predetermined distance from said vise and being adjustable as to height, said member having a horizontal supporting surface greater in 125 130

length than the length of the shears blade and having upturned stop members at each end thereof, and an abradant supporting member having a handle portion for manual actuation, whereby the abradant may be moved across said cutting blade and the member may bear at one end upon and be guided by said guide member, said

abradant supporting member having that part adapted to bear upon said guide member provided with a cutaway portion at the mid point thereof thereby reducing friction between said abradant supporting member and said guide member to a minimum.

JOHN EDGAR McKINLEY.
